DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

A method of determining the values of the term H_i in the reliability equation for a storage organization:

$$R_{\text{store}} = \sum_{f=0}^{\infty} P_f H_f$$

wherein P_f is the probability of there being f failures in the organization and wherein the values of H_f are the survival coefficients, the storage organization comprising a quantity of l words of n -bit length, and being constructed so as to correct a quantity of c errors. The method comprises:

(a) Generating survival patterns for given values of

c, f, n and l wherein there are considered all of the arrays

$$\begin{aligned} S_{11} & S_{12} \dots S_{1l} \\ S_{21} & S_{22} \dots S_{2l} \\ & \vdots \\ & \vdots \\ S_{n1} & S_{n2} \dots S_{nl} \end{aligned}$$

wherein S_{ij} is the number of failures in the i th bit of the j th word with

$$R_i = \sum_{k=1}^l S_{ik}$$

such that

$$(1) \quad R_i \sum_{i=1}^n R_i = f$$

$$(2) \quad R_i \geq R_{i+1} \text{ for } i=1, \dots, (n-1)$$

$$(3) \quad S_{ik} \geq S_{ik+1} \text{ for } k=l, \dots, (l-1)$$

and wherein the term A_m is defined as the number of $R_i = m$ for $m=0, \dots, f$, the term B_{im} is defined as being equal to the number of $S_{ik} = m$ for $m=1, \dots, f$, the term D_i is defined as

$$\sum_{m=1}^f$$

and wherein

$$\sum_{m=0}^f A_m = n$$

the primitives being modified by shifting each row thereof sufficiently to the right to fit a given set of replication numbers (X_{ij}) wherein X_{ij} is equal to the number of non-zero positions introduced for the j th time in the i th row whereby, for any given primitive, the range of replication numbers, all of which produce survival patterns, are determined as follows:

$$G_{ij} = \sum_{k=1}^i X_{kj}$$

wherein $X_{11} = D_1$ and wherein for $i > 1$

$$\sum_{j=1}^i X_{ij} = D_i$$

such that

$$(4) \quad 0 \leq X_{ij} \leq G_{i-1, j-1} - G_{i-1, j}$$

wherein $j=l, \dots, i$ and

$$(5) \quad X_{ij} = 0 \text{ wherever } j > i \text{ or } j > c$$

PUBLISHED JULY 10, 1973

(b) Calculating the number of permutations of each survival pattern in accordance with the equation:

$$H(c, f, n, l) = \frac{l_{G_{pi}} n_a - A_0}{\prod_{m=1}^f \left(A_m! \prod_{i=1}^n B_{im}! \right)} \\ \times \prod_{i=1}^n \frac{\left(\sum_{j=1}^c X_{ij} \right)!}{\prod_{j=1}^c (X_{ij})!} \times \prod_{i=1}^{n-1} \prod_{j=1}^{c-1} (G_{ij} - G_{i, j+1}) x_{i+1, j+1}$$

(c) Calculating the probability of the occurrence of each pattern in accordance with the following expression

$$\frac{f!}{(nl)^f \prod (S_{ik})!} \\ i=1, \dots, n \\ k=1, \dots, l$$

and multiplying that probability by the number of permutations; and

(d) Summing all of the products resulting from step (c) over all of the generic survival patterns.
